OF WORCESTER, MASSACHUSETTS, A CORPORATION OF MASSACHUSETTS.

MAGNET-OPERATED SWITCH.

1,271,873.

Specification of Letters Patent.

Patented July 9, 1918.

Application filed April 12, 1916. Serial No. 90,763.

To all whom it may concern:

Be it known that we, RUDOLPH C. EMMERLING, JOHN H. WHEELOCK, and CURT J. ROHLAND, said EMMERLING and WHEELOCK citizens of the United States, said ROHLAND being a citizen of the German Empire, all residing at Worcester, in the county of Worcester and State of Massachusetts, have, invented a new and useful Magnet-Operated 10 Switch, of which the following is a specification.

This invention relates to a switch or contact making device operated by an electromagnet. While capable of use with a direct current system, the invention is particularly designed for use with an alternating current, and the principal objects of the invention are to provide means of simple form and without complications whereby the current 20 alternations will be prevented from causing chattering of the contact points and interruptions to the current passing through them.

Reference is to be had to the accompanying drawing, in which—

Figure 1 is a front elevation of a preferred embodiment of this invention showing the contacts open, and

Fig. 2 is a similar view showing the contacts fully closed in full lines.

The invention is shown as applied for the purpose of closing current contact members 10 and 11. For this purpose an electromagnet 12 is shown provided with an armature 13 pivoted on a stud 14. This armature is provided with a projection 15 extending from it. This projection is shown as located on the opposite side of the pivot from the main body of the armature and is located in the plane thereof, the pivot being located at one side of this plane. This gives a good leverage and at the same time a sufficient amplitude of movement.

Pivoted on an axis parallel with the first named axis, namely on a stud 20 is a rigid arm 21. This arm is provided with a notch 22 for receiving the end of said projection 15 at certain times as will appear. Secured on this arm is a flat brass spring 23 which is connected with one of the terminals 24 of the line which is designed to be completed by the contacting of the contact members 10 and 11. The spring is shown as in line with the pivot

20. One of these members, as for example, 10, is located at the end of this spring, and 55 consequently is operated by the arm.

The operation of the device is as follows:—When there is no current in the magnet coils the arm swings down by gravity and the end of the projection of the armature is located in the notch 22 which normally assists in keeping the main body of the armature away from the electromagnet. However, it will be observed that the armature is so balanced that it normally swings 65 into this position without the aid of this arm, and moves against a stop 25. Upon the excitation of the electromagnet the armature is drawn to it about its pivot. This causes at first a comparatively rapid swinging motion 70 of the arm 21 about its pivot until the end of the projection moves out of the notch 22. Just at that time the contact member 10 comes into contact with the contact member 11 and the circuit is closed. But the armature continues to swing toward the coils of the magnet and it will be seen that this motion causes the projection 15 to wedge 75 against the pivoted arm and put the spring under tension so that the contact member 10 is held against the member 11 by a spring tension. Any slight vibrations of the armature, while they increase and reduce this tension, will not under ordinary circumstances relieve it entirely of tension. Therefore an 85 alternating current can be used in this armature without causing chattering at the contact points. This is brought about by the relative position of the parts as so far described and by the further fact that the 90 arm 21 is located in a position not quite tangent to the arc described by the projection 15 on the armature. It is moved away from it only slightly, but enough so that the motion of the armature toward the coils after 95 its projection passes out of the notch will put further pressure on the arm and spring and force the arm back out of the normal position which it would assume from the action of the spring alone. In this way the vibrations of the armature are not transmitted to the contact members, in spite of the fact that the armature itself is operated directly without intermediate mechanism. Fig. 2 shows, 100 in full lines, the position of the parts just 105 as the projection 15 comes out of the notch,

while it shows, in dotted lines, the position when the armature is drawn up as near the magnet as it will go.

We have shown the parts in each position 5 that gravity can be depended upon to open the contact but we do not wish to be limited to this.

Although we have illustrated and described only a single embodiment of the invention we are aware of the fact that many modifications can be made therein by any person skilled in the art without departing from the scope of the invention as expressed in the claims. Therefore we do not wish to 10 be limited to all the details of construction herein shown and described, but what we 15 do claim is:—

1. In an electromagnetic switch, the combination with two contact members, and an 20 electromagnet having a pivoted armature, of a movable independent arm, supporting one of said contact members, said armature having a fixed projection thereon constituting the sole means for operating said 25 movable arm in a direction to close the contact.

2. In an electromagnetic switch, the combination with two contact members, one of them movable into contact with the other, 30 and an electromagnet having a pivoted armature, of a movable arm, a spring extending from the arm and supporting said movable contact member, said armature having a projection for engaging and operating said 35 arm located in alinement with the main body of the armature and the pivot being located beyond the plane of the armature and projection.

3. In an electromagnetic switch, the combination with two contact members, of an 40 electromagnet having a pivoted armature, and a movable arm supporting one of said contact members, said armature having means for engaging and operating said arm 45 located substantially in alinement with the main body of the armature and the pivot being located beyond the plane of the armature.

4. In an electromagnetic switch, the combination with an electromagnet having a 50 pivoted armature, of an arm, a spring extending from the arm and having a contact member thereon, said armature having a projection for engaging and operating said 55 arm, the pivot being located beyond the plane of the armature, and a parallel pivot near the first named pivot but on the side thereof opposite the armature and near the end thereof on which said arm is pivoted, 60 said arm being provided with a notch for receiving said projection when the armature is not attracted toward the coils of the magnet.

5. In an electromagnetic switch, the combination with two contact members, one of 65

them movable into contact with the other, and an electromagnet having a pivoted armature, of a pivoted arm; a flat spring extending from the arm and supporting said movable contact member, said armature 70 having a projection for engaging and operating said movable arm, said projection being located in alinement with the main body of the armature and on the opposite side of the pivot therefrom, the pivot being located 75 beyond the plane of the armature, and the arm being pivoted on a parallel pivot near the first named pivot but on the side thereof opposite the armature and near the end thereof and extending past the said projection, said arm being provided with a notch 80 for receiving said projection when the armature is not attracted toward the coils of the magnet, whereby when the projection is moved out of the notch it holds the spring 85 under tension.

6. In an electromagnetic switch, the combination with two contact members, of a movable arm supporting one of them and adapted to fall away from the other by 90 gravity, and an electromagnet having an armature under said arm normally held toward but spaced from the electromagnet by gravity and provided with means thereon for engaging the under side of said 95 movable arm and forcing it up to bring said members into contact, said arm having means whereby when it falls it will hold the armature farther away from the electromagnet against the force of gravity. 100

7. In an electromagnetic switch, the combination with two contact members, of a movable arm supporting one of them and adapted to fall away from contact with the other by gravity, and an electromagnet thereunder having an upright pivoted armature independent of said arm provided with means thereon for engaging the bottom of said movable arm and forcing it up to bring said 110 members into contact.

8. In an electromagnetic switch, the combination with an electromagnet having an upright pivoted armature, of an arm having a contact member thereon, said armature having a projection above its pivot for engaging and operating said arm, the pivot being located beyond the plane of the armature, and a parallel pivot near the first named pivot but on the side thereof opposite the armature on which said arm is 120 pivoted, said arm being provided with a notch for receiving said projection when the armature is not attracted toward the coils of the magnet. 115

9. In an electromagnetic switch, the combination with two contact members, one of them movable into contact with the other, and an electromagnet having an armature, of a movable arm supporting said movable contact member, and a cam surface contact 130

between the arm and armature for operating said arm, said cam surface being arranged to hold the armature away from the electromagnet normally when the contact members are separated.

10. In an electromagnetic switch, the combination with two contact members, one of them movable into contact with the other, and an electromagnet having a pivoted armature, of a movable arm supporting one of said movable contact members, said arma-

ture having means for engaging and operating said arm located substantially in alignment with the main body of the armature and the pivot being located on the side of 15 the armature opposite the electromagnet.

In testimony whereof we have hereunto set our hands.

RUDOLPH C. EMMERLING.
JOHN H. WHEELOCK.
CURT J. ROHLAND.
